DISPLAY CASE FOR SPECTACLE-FRAMES OR THE LIKE

Lyons I. Jossem, Rochester, N. Y.

Application May 31, 1955, Serial No. 36,296

Term of patent 7 years

(Cl. D80—11)

Fig. 1 is a front perspective view of a display case for spectacle frames or the like, showing my new design;

Fig. 2 is a rear perspective view of the case;

Fig. 3 is a view similar to Fig. 2 but showing the back of the display case opened;

Fig. 4 is a front elevational view, showing in broken lines a spectacle frame on display in the case, the broken lines being for illustrative purposes only; and

Fig. 5 is a section taken on the line 5-5 of Fig. 4 and looking in the direction of the arrows.

I claim:

The ornamental design for a display case for spectacle frames or the like, as shown and described.
